DRAIN FOR INSULATED PICNIC COOLER

William H. Plamann, Wichita, Kans., assignor to The Coleman Company, Inc., Wichita, Kans., a corporation of Kansas

Filed Feb. 18, 1963, Ser. No. 73,601

Term of patent 14 years

(Cl. D58—17)

FIG. 1

FIG. 2

FIG. 4

FIG. 3

FIG. 5

FIG. 1 is a front elevational view of a drain for insulated picnic cooler showing my new design;

FIG. 2 is a fragmentary front elevational view thereof on an enlarged scale;

FIG. 3 is a fragmentary front elevational view thereof with the drain plug in open position;

FIG. 4 is a fragmentary top plan view thereof; and

FIG. 5 is a fragmentary side elevational view thereof.

The portions shown in broken lines are for illustrative purposes only.

I claim:

The ornamental design for a drain for insulated picnic cooler, as shown and described.
